UNITED STATES PATENT OFFICE.

CHARLES JABLOW, OF EAST PITTSBURGH, AND FRANK L. ALBEN, OF WILKINSBURG, PENNSYLVANIA, ASSIGNEES TO WESTINGHOUSE ELECTRIC AND MANUFACTURING COMPANY, A CORPORATION OF PENNSYLVANIA.

CENTER PIN.

Application filed September 20, 1923. Serial No. 663,784.

To all whom it may concern:

Be it known that we, CHARLES JABLOW, a citizen of the United States, and a resident of East Pittsburgh, in the county of Allegheny and State of Pennsylvania, and FRANK L. ALBEN, a citizen of the United States, and a resident of Wilkinsburg, in the county of Allegheny and State of Pennsylvania, have invented a new and useful

10 Improvement in Center Pins, of which the following is a specification.

Our invention relates to railway vehicles, and more especially to center pin mountings for the cab and truck members that provide 15 freedom of movement therebetween and further support the vehicle body on its drive trucks.

It is among the objects of this invention to provide a center pin for railway vehicles 20 which shall permit relative swivelling, rolling, vertical and longitudinal movement of the co-operating truck and body members, which shall be adapted to yieldingly carry the load of the cab and which shall be 25 of simple, compact and durable construction to adequately meet the severe working stress to which it may be subjected.

In designing a center pin structure for 30 railway vehicles, under certain conditions it is essential to provide for adequate bearing surface, for swivel, rolling, vertical and limited longitudinal movements, and for suitable lubrication of the several co-operating parts.

35 Our present invention is directed to a center pin which meets these requirements in that it provides a relatively large bearing surface, yieldingly restrains vertical movement, permits rolling of the pin member in 40 a direction transversely of the longitudinal axis of the cab frame and further permits of limited longitudinal movement relative to the supporting trucks.

In the accompanying drawings constituting 45 a part hereof and in which like reference characters designate like parts;

Figure 1 is a view, partially in side elevation and partially in cross-section, of a fragmentary portion of a railway vehicle embodying the principles of our invention and

50 Fig. 2 is a view thereof, partially in end elevation and partially in cross-section.

Referring to Fig. 1, the structure therein

illustrated comprises a truck frame 1 that is provided with vertical pedestal jaws 2 having journal boxes 3 disposed therein for journaling the wheeled axles 4 in the usual manner. A box-shaped cross-tie 5 is secured at its flanged ends 6 to the truck frames 1 by suitable bolts 7. The cross-tie 5 is provided with a central relatively deep recess 8 and a plurality of outer relatively shallow recesses 9. A vertically slideable bearing pad 10 is mounted in the recess 8 and is provided with a groove 11 running along the longitudinal axis of the truck. The outer walls of the bearing pad extend upwardly to constitute an annular flange 12. A plurality of coil springs 13 are interposed between the cross-tie 5 and the flange 12 of the pad 10 to yieldingly support the latter. The lower ends of the springs 13 are disposed in the recesses 9.

A center pin 14 of substantially T-shape, having a convex or cylindrical seating surface 15 corresponding to and seated in the groove 11 of the pad 10, is pivotally mounted in a cylindrical recess 16 of a bracket 17, which is suitably secured to the sub-frame of the vehicle body or cab 18. The cylindrical head 15 is shorter than the walls of the recess 8 to provide a clearance space 19 therebetween, which permits slight longitudinal movement of the pin on the pad 10. A plate 20 is bolted to the cross-tie 5 to provide a cover that prevents access of dirt to the bearing of the center pin and also prevents the parts from separating.

The center pin 14 is lubricated by a pipe 21 which extends into the cab 18 and may be connected to a suitable source of lubrication such as an oil reservoir or pump.

It is obvious from the above description of our invention that the spring-borne bearing pad 10 permits yielding vertical movement between cab 18 and cross-tie 5 and that the cylindrical head of the center pin 14 permits rolling movement of the cab 18 on the truck support. The upper cylindrical portion of the center pin and its co-operating bracket 17 permit swivel movement of the truck relative to the vehicle body and the clearance space 19 between the center pin and recess in the cross-tie allows limited longitudinal movement, which is necessary when the vehicle passes from a tangent to

a curve. This design lends itself to rugged construction and the wearing surfaces are accessible for lubrication.

Although we have described a specific embodiment of our invention, it will be obvious to those skilled in the art that various modifications may be made in the details of construction without departing from the principles herein set forth. For instance, 10 any suitable spring mounting may be substituted for the coil springs 13, or the brackets 17 may be an integral part of the subframe of the vehicle body, and other modification of the cross-tie may be utilized 15 in place of that shown.

We claim as our invention:

1. A center pin structure for railway vehicles comprising means for providing relative swivelling and rolling, longitudinal and 20 vertical movement of the cab and truck frame.

2. A center pin structure for railway vehicles comprising means for providing relative rolling, longitudinal and resilient vertical movement of the cab and truck frame. 25

3. A center pin structure for railway vehicles comprising a cylindrical bracket secured to the cab under frame, a cross-tie having a recess in alignment with said bracket, 30 a center-pin disposed in said cylindrical bracket and adapted to swivel therein, a vertically movable pad disposed in the re-

cess of said cross-tie, and a plurality of yielding supports interposed between said pad and cross-tie. 35

4. A center pin structure for railway vehicles comprising a cylindrical bracket secured to the cab under frame, a cross-tie having a recess in alignment with said bracket, and a center pin associated with said bracket 40 and cross-tie and having a cylindrical T-shape head.

5. A center pin structure for railway vehicles comprising a pin of substantially T-shape having a cylindrical seating surface, 45 a spring-borne pad disposed in a recess of a cross-tie of the truck frame and having a cylindrical surface to engage said pin and a cylindrical bearing on the cab frame to engage said pin. 50

6. A center pin structure for railway vehicles comprising a pin of substantially T-shape having a cylindrical seating surface, and a cylindrical cooperating bearing pad, 55 said pin being pivotally mounted underneath the cab frame and said pad being movably mounted in a recess of a cross-tie, and a plurality of springs for supporting said pad upon said cross-tie.

In testimony whereof, we have hereunto 60 subscribed our names this 13th day of September, 1923.

CHARLES JABLOW.
FRANK L. ALBEN.
